UNITED STATES PATENT OFFICE.

JAMES M. BRESEE, OF MATTOON, ILLINOIS.

ROAD-GRADING MACHINE.

1,128,654.

Specification of Letters Patent. Patented Feb. 16, 1915.

Application filed May 1, 1913. Serial No. 764,777.

To all whom it may concern:

Be it known that I, JAMES M. BRESEE, a citizen of the United States, residing at Mattoon, in the county of Coles and State of Illinois, have invented certain new and useful Improvements in Road-Grading Machines, of which the following is a specification.

My invention relates to road-leveling and grading machines, and has for its object the drawing or dragging in of the dirt from both sides of a road and depositing it in the center or distributing it over the road, as desired.

My invention is especially adapted to use with traction engines, and is designed to work upon a quantity of dirt which would equal the capacity of traction engines, in common use.

My invention is designed to follow the engine which travels upon the center of the road. It is provided with long cutting blades, which reach both sides of the road and converge rearwardly to deposit the dirt collected at the center of the road. The dirt thus deposited is then leveled and smoothed down by a drag which follows the scraper.

Other objects and advantages of my invention will be rendered apparent from the following specification, when taken in connection with the accompanying drawings, in which—

Figure 1 is a plan view of the road-leveling machine. Fig. 2 is a side elevation of the same. Fig. 3 is a front elevation of the same. Fig. 4 is an elevation of the longitudinally sliding block. Fig. 5 is a plan view of the same. Fig. 6 is a sectional view of one of the scrapers, showing in elevation its operating link. Fig. 7 is a fragmentary elevation of the same. Fig. 8 is a fragmentary plan of the same. Fig. 9 is a cross sectional view of the sliding block and its guides. Fig. 10 is a sectional view of the transverse supporting bars and guide rail. Fig. 11 is a plan view of the intermediate portion of said transverse bars and guide rail. Fig. 12 is an elevation of the outer end of one of the guide rails showing a supporting roller for one of the bars. Fig. 13 is a plan view of the same.

My improved road machine comprises two long scraper bars 15 and 16 at either side of the machine, said bars being spread apart a considerable distance at their forward ends and converging at their rear ends. Imme-

diately behind the said rear ends I provide a drag comprising leveling plates or boards 17 and 18. The forward ends of the scraping bars are moved outwardly and inwardly and held in the desired spaced relation by the links 19 and 20 which are pivotally attached to said bars at 21 and 22, respectively. The inner ends of said links 19 and 20 are pivotally attached at 23 to a sliding block 24 which is adapted to move longitudinally along the center of the machine.

The sliding block 24 is provided with guide bars 25 and 26, preferably of angle form, suitably attached to the body of the machine. The sliding block is given its longitudinal movement by a sprocket chain 27 running over sprocket wheels 28 and 29 in the forward and rear portions, respectively, of the body. The large hand wheel 30 within convenient reach of the operator, when he stands in the forward portion of the machine, is rigidly connected with the sprocket wheel 28 and provides convenient means for causing the sliding block to move longitudinally and thereby to produce an outward or inward movement of the scraping bars, as may be desired.

The forward ends of the scraping bars are supported by transversely movable bars 31 and 32 which are carried in a guideway 33, preferably of channel form mounted upon the forward end of the body. The movable bars 31 and 32 are provided with pulleys 37 at their outer ends over each of which a cable 34 is placed and which passes around another pulley 38 attached to the scraper. This cable is attached at its end to the transverse bar at 39. A hand wheel 35 mounted upon the forward portion of the machine provides a means for winding up the cable and raising the scraper bar.

The rear portions of the scraper bars are raised by a cable 40, which may be wound around a drum 41 by the hand wheel 42. The cable 40 passes around the pulley 43 mounted upon the rear portion of the body and around a pulley 44 attached to the transverse link 85, which is pivotally attached at its ends to the scrapers.

The scrapers are propelled forwardly by means of the chains 46 and 48, which are attached at 47 and 49, respectively, to the body frame members 50 and 51. The chains 46 and 48 are attached at opposite sides of the body and are arranged so that they cross

when they are attached to the scrapers. In this way lateral swaying of the scrapers is resisted.

The transverse guide channel 52 is supported by the upright members 53 and 54 which are secured to the main body members 50 and 51. Diagonal braces 55 and 56 render the said guide channel 52 rigid. At the outer ends of said guide channel are placed the supporting rollers 57 and 58 on which the transversely movable supporting bars 31 and 32 slide.

The inner ends of the transverse bars 31 and 32 are held downwardly in close relation to the guide channel 52 by the roller 60, which is mounted in the short inverted channel bar 59. This short channel bar is secured to the lower channel bar 52. The upward tendency of the inner ends of the supporting bars 31 and 32 is caused by the weight of the scrapers which are suspended to them at their outer ends by the cables 33 and 34.

Upon the inner faces of the webs of the I-beams, of which the bars 31 and 32 are composed, are secured rack bars 61 and 62. These rack bars mesh with a single pinion 63 which is secured to a vertical shaft 64 at the upper end of which is secured the hand wheel 65. The hand wheel is placed within convenient reach of the operator and by means thereof he can move the bars 31 and 32 outwardly or inwardly, as occasion demands. When the machine is being transported from place to place without being operated, it is desirable to move the scrapers into close relation to the body of the machine. The hand wheel 65 permits this to be done and also permits the said scrapers to be properly supported at various positions according to the width of the road that is being leveled. In order to retain the said bars in their adjusted positions, a locking device comprising a notched wheel 66 is provided. This wheel is secured to the upright shaft 64. The end of the lever 67 is adapted to drop into any one of said notches and can be released therefrom by the foot lever 69 which is connected to the outer end of said lever 67 by a rod 68. The inner portion of the lever 67 is made longer and heavier than the outer end in order that gravity may cause it to drop into position in one of the notches when the foot is raised from the lever 69.

The links 19 and 20 are bent downwardly and inwardly at their ends, as shown at 70 in Fig. 6, to engage the lower rear portions of the scrapers. The extreme lower and inner end of each link is provided with an eye through which a bolt or pin 22 is inserted. Said pin passes through an aperture in the lug 72 above the eye and through a corresponding aperture in the angle bar 71 below said eye. The angle bar 71 is at-

tached to a channel bar 73 secured to the back face of the curved scraper 74. Both the channel bars 73 and 71 extend throughout the greater portion of the length of the scraper. The scraper 74 may be made of sheet metal in sections and secured to the channel bar 73 in any suitable manner, preferably by countersunk screws.

The inner portion of each of the links 19 and 20 may be made of a lighter bar of metal, preferably an angle bar, as shown at 75. The outer portion may be forged from a bar of steel into the curved form shown. The innermost ends of the angle bar portion 75 are provided with eyes 76, 77, which pivotally engage the pin 23 which is rigidly secured to the sliding block 24.

The sliding block 24 is attached to the sprocket chain 27 by means of the recessed washers or blocks 78 and 79 which are inserted in the aperture of one of the links of the chain. A nut 80 threaded on the lower end of the pin 23 permits said washers to be wedged into place in said link. The said nut also causes the shouldered portion 23^a to be drawn tightly against the upper surface of the sliding block, thereby causing the pin 23 to be rigidly secured in the said block.

The downwardly projecting portions 24^a and 24^b of the sliding block are fitted to the longitudinal angle bars 25 and 26 upon which said block slides and by which it is guided. The clips 81 and 82 are extended below the lower surface of the said angle bars and prevent the sliding block becoming displaced therefrom.

The hand wheels 35 may be provided with a locking device corresponding in all respects with the locking disk 66 and the lever 67 engaging the same. The hand wheel 42 is provided with a similar locking device 84 and the hand wheel 30 is provided with a locking device 83.

The rear wheels 86 and 87 are placed relatively close together, while the forward wheels 88 and 89 are placed relatively far apart. With this arrangement it will be noted that the rear wheels have a narrow wheel base corresponding to the close relation of the scrapers at their rear ends. The widely separated wheels at the forward end correspond to the widely separated forward ends of the scrapers, thereby efficiently supporting them.

In the operation and use of my improved road scraper, the operator takes his position at the forward end of the machine within easy reach of the hand wheels 30, 42, 35, 35^a and 65. By means of the hand wheel 30 he is enabled to cause the sliding block 24 to move backwardly and forwardly and the scrapers 15 and 16 to move inwardly or outwardly. In roads of great width the scrapers may be moved to a widely diverging position, as indicated in dotted lines in Fig. 1.

When it is desired to scrape a narrower road they may be moved inwardly to the position shown in solid lines, or to any intermediate position. During the manipulation of the 5 scrapers, as above described, they may be elevated or lowered by the hand wheels 35 and 35^a. At the same time the supporting bars 31 and 32 may be moved inwardly or outwardly in order that the pendant position 10 of the cables 33 and 34 may not be too angular and thereby interfere with the proper operation of the scrapers.

The curved form of the links 20 permits the driving force to be transmitted to the 15 scrapers in their various positions without undue twisting or warping thereof. The lowermost end of the links may be rounded, as shown in dotted lines at 90, and said curved end may bear upon the angle bar 71 20 to relieve the pressure upon the pin 22. The horizontal portions 75 of the links will move freely above the body frame members 50 and 51 without interference therewith.

At the extreme forward end of the frame 25 a tool-box 91 is provided and a suitable tongue or other connecting means 92 for the attachment of the traction engine or other propelling appliance.

While I have described more or less precisely the details of construction, I do not wish to be understood as limiting myself thereto, as I contemplate changes in form and the proportion of parts and the substitution of equivalents as circumstances may 35 suggest or render expedient without departing from the spirit of my invention.

I claim:

1. In a device of the class described, a body, a scraper carried by said body, means 40 movable longitudinally of said body to positively move said scraper to and from said body, and means movable transversely of said body to raise or lower said scraper.

2. In a device of the class described, a 45 wheeled body, scrapers angularly disposed on opposite sides of said body and converging rearwardly, means for pivotally connecting the rear portions of said scrapers, a longitudinally sliding member on said body, means connecting said member with the forward portion of each of said scrapers, and means for elevating the forward portions of said scrapers, said means being movable transversely of said body to accommodate 50 the transverse movements of said forward portions of said scrapers.

3. In a device of the class described, a body, a pair of wheels relatively wide apart at the forward portion of said body, a second pair of wheels relatively close together at the rearward portion of said body, scrapers located on each side of said body outside of said wheels, said scrapers extending from adjacent the front of said body to a point a 55 considerable distance rearwardly of said

rear wheels and being pivotally connected at their rearward portions, and means movable longitudinally of said body to swing said scrapers about their pivotal connections to and from said body while said pivotal point 70 remains substantially fixed relatively to said body.

4. In a device of the class described, a body, a scraper carried by said body, means movable longitudinally of said body to positively adjust the inclination of said scraper with respect to said body, and means movable outwardly of said body in a plane transversely of the longitudinal axis thereof to raise and lower said scraper and support the 80 forward end thereof.

5. In a device of the class described, a wheeled body, scrapers angularly disposed on opposite sides of said body and converging rearwardly, means for pivotally connecting the rear portions of said scrapers, a longitudinally sliding member on said body, links connecting said member with the forward portions of said scrapers, means for elevating the forward portions of said 85 scrapers, said means being movable transversely of said body to accommodate the transverse movements of said forward portions of said scrapers, and manually actuated elements for operating said elevating 90 means and for producing said transverse movements, respectively.

6. In a device of the class described, a wheeled body, scrapers angularly disposed on opposite sides of said body and converging rearwardly, means for pivotally connecting the rear portions of said scrapers, a longitudinally sliding member on said body, links connecting said member with the forward portions of said scrapers, and 100 means for elevating the forward portions of said scrapers, said means being movable transversely of said body to accommodate the transverse movements of said forward portions of said scrapers.

7. In a device of the character described, a wheeled body, scrapers angularly disposed on opposite sides of said body and converging rearwardly, a transversely disposed supporting member above said body, transversely movable bars mounted to move bodily on said member, and means coacting with said bars for elevating said scrapers, said means being supported independently of 115 said transversely movable bars.

8. In a device of the character described, a wheeled body, scrapers angularly disposed on opposite sides of said body and converging rearwardly, a transversely disposed supporting member above said body, transversely movable bars mounted to move bodily on said member, means coacting with said bars for elevating said scrapers, said means being supported independently of 120 said transversely movable bars, and means 130

manually operated for moving said bars transversely of said body.

9. In a device of the character described, a wheeled body, scrapers angularly disposed on opposite sides of said body and converging rearwardly, a transversely disposed supporting member above said body, transversely movable bars mounted on said member, means coacting with said bars for elevating said scrapers, said means being supported independently of said transversely movable bars, means manually operated for moving said bars bodily and transversely of said body, and means for locking said last named means.

10. In a device of the character described, a wheeled body, scrapers angularly disposed

on opposite sides of said body and converging rearwardly, a transversely disposed supporting member above said body, transversely movable bars mounted on said member, means carried by said bars for elevating said scrapers, a longitudinally movable member on said body, and links pivotally attached at their inner ends to said member and at their respective outer ends to said scrapers. 20 25

In testimony whereof, I have subscribed my name.

JAMES M. BRESEE.
